COVER LIFTER

Arthur C. Shafer, Rockaway, N. J.

Application November 4, 1942, Serial No. 464,504

3 Claims. (Cl. 81—3.46)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a cover lifter.

The practice exists of storing smokeless powder in heavy metal containers, which are usually called boxes. The top of a commonly used box is provided with a round opening through which the smokeless powder is introduced into or removed from the box. This opening is provided with a short neck upon which the metal cover is secured by suitable clamping means, with a rubber gasket between the cover and the top of the neck. This forms an air-tight closure of the box. When smokeless powder has been so sealed in a box, it has been found that after a time a vacuum or partial vacuum forms within the box, making it very difficult to remove the cover after the clamping means have been removed or loosened.

Owing to the fact that these heavy metal boxes may be made of sheet steel, or galvanized sheet steel, an indiscriminate use of tools in forcing or prying the cover open is not advisable, since such action may occasion a spark by metal striking or rubbing against metal. Such a spark may ignite the powder within the container and cause an explosion.

Among the objects of the present invention is to provide a tool by the use of which these covers of powder boxes are easily lifted from the openings they close. A further object of the invention is to so construct such a tool that a spark is not likely to be produced in using it for the purpose intended.

While the present invention is particularly useful in lifting the covers of smokeless powder boxes which are held down owing to a vacuum or partial vacuum existing within the powder box, it is not to be considered as limited to this specific use. The invention may be applied to lifting tight covers from containers having other materials within them and which are difficult to lift owing to a partial vacuum or other cause.

An embodiment of the invention, applied to the lifting of the cover of a heavy sheet metal smokeless powder box, is illustrated in the accompanying drawing. In the drawing,

Figure 1 is a vertical section of a part of the top of a powder box with the cover lifter of the present invention in elevation.

Figure 2 is an elevation of the cover lifter of the present invention with the handle somewhat

depressed from its position in Figure 1, and with a part of the base in section.

Figure 3 is a plan of the handle and of parts fixed thereto.

Figure 4 is a plan of the brace or base to which the handle is pivoted.

Figure 5 is an enlarged end elevation of Figure 2 looking from the left of that figure.

Figure 6 is a plan view of Figure 1 on a reduced scale, showing how the brace of the device may be positioned between a corner of the powder box and the cover.

Referring to the drawing, the numeral 1 indicates the top of a smokeless powder box constructed of heavy gauge sheet steel. The numeral 2 indicates the box's side wall which extends above the top of the box to form a rim or chime 3 completely around the top. The top of the box is provided with a round opening 4 within which a short neck 5 is fitted and secured. The top of neck 5 is shown provided with a shoulder 6 which extends completely around the neck. A round cover 7 is provided to close the opening in the neck. This cover is rolled over around its periphery to form an inverted U-shaped depression or groove which holds the rubber ring gasket 8. The parts are so related that the gasket fits on top of the neck 5 and is pressed between the latter and the top 7 when the top 7 is clamped down. In Figure 1, the gasket appears as if pressure is applied to cover 7 from above. The horizontal cross-section of a smokeless powder box is usually a rectangle with rounded corners, and the top is of this shape also. The neck 5 is usually nearer to one of the shorter edges of the top than to the other.

The cover lifter comprises a handle 9 of steel, a lug or ear 10 of steel brazed to the handle 9 near one end, a nose 11 of brass brazed to the rod 9 at the end near the lug 10, and a brace or base indicated generally by the numeral 12 made entirely of brass.

The brace or base 12 consists of a brass rod or bar 13 to one end of which a cross bar or rod 14 of brass is brazed. The opposite end of rod 13 is slotted at 15 in a plane forming a right angle with the plane of the bar 14, thereby forming two ears 16. A hole 17 is drilled through these two ears, and a manganese bronze pin 18 passes through these two holes with a drive fit. As shown in Figures 1 and 2, the bottom of cross bar 14 is flush with the bottom of rod 13, so that the brace or base of which they form part will rest without rocking on a plane surface to which the brace may be applied. The cross bar 14 may

be bent in the form of an arc in order to permit that end of the brace to fit against a curved abutting surface, such as a circular rim or a circular portion of a rectangular rim with rounded corners.

The brass nose 11 consists, in the embodiment of the invention illustrated, of a short piece of round rod. This nose is secured at right angles to the end of the steel rod by brazing, and the axis of this rod is parallel or substantially parallel with the axis of the pin 18 and with the plane of base 12 or of cross bar 14 when the parts are assembled as shown in Figures 1 and 2. Considered from the operating position, the nose 11 projects from the top, and the ear 10 projects from underneath, of the operating handle 9.

The ear 10 on the handle 9 fits with a sliding fit in slot 15 of the rod 13, and is provided with a drilled hole through which the pin 18 passes. The ear 10 and handle 9 attached thereto rock on pin 18 as a pivot. The dimensions of the ear 10 are such that its free end is short of the bottom of the slot 15 at every position to which it may be rocked in use. See Figures 1 and 2. This condition prevents the steel ear from coming into contact with the metal top of the powder box. To further elevate the free end of the ear 10 from the bottom of slot 15, the hole 17 in the rod 13 may be drilled a little above the longitudinal axis of the rod.

A knob 19 of brass may be secured to the handle 9, and it is advantageous to chamfer the end of the handle at 20. In situations where the character of the metals from which the parts of the device are made are of no concern, all the

various parts may be made of steel or other suitable metal.

In use, the cover lifter is placed on the top 1 of the box, with the nose 11 engaged under the 5 edge of the cover and with the cross bar 14 abutting against a straight or curved portion of the rim 3, as shown in Figure 1. The handle 9 is then depressed to lift the cover.

I claim:

- 10 1. A cover lifter comprising an operating handle, an ear projecting from underneath said handle near one end, a base comprising a brass bar to one end of which said ear is pivoted, a brass cross bar at the other end of said bar, and 15 a brass nose at that end of said handle to which said ear is near and projecting above said handle.
2. A cover lifter comprising an operating handle, an ear projecting from underneath said handle near one end, a base comprising a bar to 20 one end of which said ear is pivoted, a cross bar in the form of an arc at the other end of said bar, and a nose at that end of said handle to which said ear is near and projecting above said handle.
- 25 3. A cover lifter comprising an operating handle, an ear fixed upon and projecting beneath said handle near one end, a base to a portion of which said ear is in pivotal connection and having an arcuate portion removed from 30 said pivotal connection in a direction substantially perpendicular to the axis of rotation of said pivotal connection, and a nose at that end of said handle to which said ear is near and projecting above said handle.
